[57] ABSTRACT

The typewriter has type bars with key levers and guide and return means for the key levers. The guide and return means are constituted by flexible guide parts arranged in two substantially parallel rows and extending over the whole width of the machine keyboard. The guide parts are fixed by one of their ends on a support rigidly fixed to the frame of the machine, whilst their free outer ends cooperate with the said type levers.

STRIKING DEVICE FOR A TYPEWRITER

The present invention relates to striking devices for typewriters.

In striking devices of known types for typewriters, the key levers are generally pivoted to the frame and restored by a spring into resting position. In addition to the pivot, guide means are provided to avoid lateral play of these levers.

It is an object of the present invention to provide a very simple and economic method of ensuring at the same time and with minimum of play at the pivot, the guidance and restoring of the key levers. It enables the production of key levers of small inertia with parallel guidance of the key having little frictional loss.

According to the invention, there is provided a striking device for a typewriter with type bars comprising key levers and guide and return means for the said key levers, characterized in that the said guide and return means are constituted by flexible guide parts, arranged in two rows substantially parallel between themselves and extending over the whole width of the keyboard of the machine, the said guide parts being fixed, by one of their ends on a support rigidly fixed to the frame of the machine, whilst their free ends cooperate with the said key levers.

In order that the invention may be more fully understood, several embodiments of striking devices according to the invention are described below, purely by way of illustrative but non-limiting example, with reference to the accompanying drawings, in which:

FIG. 1 is a side view of one embodiment of a striking mechanism according to the invention;

FIG. 2 is a partial view from below of FIG. 1;

FIG. 3 is a rear view, on a large scale, of a detail of FIG. 1;

FIG. 4 is a side view of a different embodiment.

The device shown comprises key levers 1 each bearing an actuating key 2 of the striking mechanism. Each key lever 1 has, at one of its ends, a finger 3 capable of being engaged in a guide slot of a front comb 4. At its other end, the key lever 1 is guided by two fingers 5 and 6 engaging in guide slots 7, 8. These guide slots constitute a rear comb 9 forming one of the arms of a support 10 in the general shape of a U rigidly fixed to the frame, not shown, of the machine and arranged in front of the keyboard. On the other or front arm 11 of the U-support 10 are fixed two rows of identical flexible strips 12, 13 substantially parallel to each other. The upper row 12 is fixed at the point of origin of the arm 11 of the U whilst the lower row 13 is fixed to the curved end 15 of the said arm. The free ends of the strips of these rows extend to the vicinity of the opposite arm or comb 9 of the U-shaped support 10.

The strips 12 and 13 of each of the two rows of strips are cut out of two strips of metal or plastic material and constitute combs fixed respectively at 14 and at 15 on the U-support 10, by strips 12' and 13' screwed or riveted onto the said support. The free ends of the flexible strips 12 and 13 are provided with apertures 16 in which are engaged the free ends 5' and 6' of the fingers 5 and 6 of the key lever 1.

This arrangement enables very simple assembly of the key levers on the U-support 10 on which the two rows of flexible strips 12 and 13 have been previously fixed. It suffices to insert the fingers 5 and 6 of each key lever into the slots 7 and 8, the strips 12 and 13 having

been previously bent downwardly, then to guide the ends 5' and 6' of these fingers into the corresponding apertures 16 of the strips 12 and 13. The fingers 5 and 6 being normally centered in the slots 7 and 8 by the flexible strips, these slots only contribute to the guidance when abnormal forces are exerted on the keys, which forces are manifested by twisting of the flexible strips. Under these conditions of normal actuation, frictional forces are therefore very slight.

The striking device also comprises an actuating lever 17 of arched shape, pivoting around a rod 18. This lever is restored to a rest position by a spring 19 against the stop 20 on which it is supported by its heel 21. The stop 20 is fixed to an extension 22 of the front comb 4.

15 The actuating lever 17 has, close to its pivoting rod 18, a hole 23 for a pin 24 rigidly fixed to an arm 25 mounted pivotably at 26. This arm 25 places in motion, through a pull rod, not shown, a type bar, also not shown, for effecting the impression of the type element 20 concerned.

In the neighbourhood of the end of the actuating lever 17 opposite the pivoting pin 18 is mounted a catch 27 pivoting around a screw 28, of which the nose 29 is capable of cooperating with the teeth 30 of a splined actuating shaft 31 for continuous rotation in the direction of the arrow B. The catch 27 is held in the rest position, shown in FIG. 1, by means of a jump spring 32 engaging, on one hand, in a slot provided on the catch 27 and, on the other hand, in a groove provided 25 at the end of the arched lever 17. In this rest position, the catch 27 is supported on the arched lever 17 by means of a stop 33 rigidly fixed to this catch.

On the key lever 1 is mounted a catch 34 pivoting around a pin 35 and of which the nose 36 is capable of cooperating with a heel 37 of the catch 27, so as to cause the latter to pivot. The catch 34 is held in rest position by a spring 38 fixed on the key lever 1. In this rest position, the catch 34 comes into abutment against a heel 39 possessed by the said key lever.

40 The operation of the mechanism is as follows:

Pressure exerted on a key 2 of the keyboard displaces vertically, in the direction of the arrow A, the key lever 1 against the restoring action of the parallel flexible strips 12 and 13. The movement of the key lever 1 is limited by the abutment of its finger 3 against the bottom of the slot 4. The flexible strips 12 and 13 bend and then take up the positions indicated in dashed line in FIG. 1. On the downward movement of the lever 1, the catch 34 displaces the catch 27 to bring its nose 29 into the path of the teeth 30 of the actuating shaft 31. A tooth 30 then pushes the catch 27 which drives the arched lever 17 in the direction of the arrow C in opposition to the spring 19.

55 The movement of the lever 17 is transmitted to the arm 25 through the pin 24. The edge of the hole 23 forms a ramp enabling progressive acceleration of the arm 25 and of the type bar. At the end of the stroke of the lever 17, the catch 27 comes into abutment against a pin 151, which restores the catch into its initial position, against the effect of the jump spring 32. The lever 17 is then restored into resting position by the spring 19.

60 FIG. 4 illustrates another embodiment of the striking device, in which the return and guide means of each key lever 1' are constituted by a guide part 40, made of synthetic material, having two parallel flexible arms 41 and 42 connected by a web or median portion 43.

Each guide part 40 is engaged by its median portion 43 in a slot 51 of a rear comb 48 fixed to the frame of the machine, not shown. In addition, the guide part 40 is mounted on two transverse parallel fixed pins 44 and 45, respectively engaged in two holes of the median portion 43 at the height of the arms 41 and 42. The two parallel pins 44 and 45 are fixed to the rear comb 48 by flanges, not shown, distributed over the length of the comb. On the other hand, the guide part 40 is hinged at the end of its flexible arms 41 and 42 through two pins 46' and 47' engaging in two holes provided respectively on two lugs 46, 47 with which the key lever 1' is provided and which engage in two guide slots 49, 50 of a rear comb 48.

In the resting position of each key, the guide part 40 which is associated with it is in a state of tension sufficient for the flexible arms 41 and 42 to exert on the key lever 1 a return force sufficient to hold this lever in abutment by its lug 46 against the bottom of the guide slot 49.

The other guide parts 40 corresponding to the other key levers, not shown, are mounted side by side, each in a slot of the rear comb 48, on two fixed transverse pins 44 and 45, which are arranged parallel to the cylinder, not shown, of the machine. In this embodiment, the drive mechanism of the type bar is identical with that of FIG. 1.

It suffices to mount firstly on each type lever 1' a guide part 40 by introducing the two pins 46' and 47' into the corresponding holes of the lugs 46 and 47. This assembly is then placed in the slots 49, 50 and 51 of the rear comb 48, the width of the slots 49 and 50 no longer permitting the pins 46' and 47' to be disengaged from the lugs 46 and 47. When all the key levers are in position, the two transverse pins 44 and 45 are threaded into each of the holes provided on the median portion 43 of the parts 40. The shape of these parts 40 is such that, when they are held in place by the pins 44 and 45, their arms 41 and 42 are elastically deformed and exert the role of a return spring for the key levers whilst insuring guidance of the said levers by the parallelogram arrangement.

I claim:

1. A striking device for a typewriter provided with a plurality of typebars, a keyboard including a plurality of key levers attached to flexible means for the guiding and recall of each said key lever, a rigid U-shaped sup-

port fixed relative to the frame of the typewriter and provided with a front arm and a rear arm, said flexible means comprising at least two rows of substantially parallel resilient strips, said strips each having one end fixedly attached to said support adjacent said front support arm, said strips each having an opposite free end attached to each said key lever adjacent said rear support arm, said rear support arm including guide slots engageable by each said key lever adjacent the point of attachment between said strip free ends and said key levers, and said strips forming each said row are cut from a single piece of resilient material.

2. A device according to claim 1, wherein, each set key lever includes fingers disposed within said guide slots, said strip free ends each provided with an aperture, and the end portion of each said finger is disposed within one said strip aperture to provide said point of attachment between said strips and key levers, whereby said strips maintain the positioning of said key levers within said guide slots.

3. A striking device for a typewriter with a plurality of type bars, a keyboard including a plurality of adjacent key levers attached to flexible means for the guiding and recall of each said key lever, a rigid rear comb support member affixed to the frame of the typewriter and provided with guide slots engageable by each said key lever adjacent the point of attachment between said flexible means and said key levers, said flexible means comprising for each said key lever a U-shaped resilient member including a pair of parallel arms each having a free end attached to each said key lever adjacent each said guide slot, each said pair of parallel arms connected by a web portion fixed relative to the frame of the typewriter, a pair of lugs on each said key lever pivotably connected to a respective pair of said parallel arm free ends, and said lugs are each disposed in one said slot of said rear comb support member, whereby, said parallel arms maintain the positioning of said key levers within said guide slots.

4. A device according to claim 3 including, a pair of parallel pins affixed to the frame of the typewriter and extending the entire lateral extent of the plurality of key levers, and the ends of each of said web portions connecting said pairs of parallel arms are mounted on said pair of parallel pins.
